UNITED STATES PATENT OFFICE.

LORNE A. GRIFFIN, OF EVANSTON, ILLINOIS, ASSIGNOR TO AMERICAN STEAM CONVEYOR CORPORATION, OF CHICAGO, ILLINOIS, A CORPORATION OF NEW YORK.

ASH-CONVEYER.

1,331,986.

Specification of Letters Patent. Patented Feb. 24, 1920.

Application filed August 4, 1919. Serial No. 315,290.

To all whom it may concern:

Be it known that I, LORNE A. GRIFFIN, a citizen of the United States, and resident of Evanston, in the county of Cook and State of Illinois, have invented a certain new and useful Improvement in Ash-Conveyers, of which the following is a full, clear, and concise description, reference being had to the accompanying drawings, forming a part of this specification.

My invention relates to ash conveyers of the conduit type wherein the ash is conveyed through the conduit by the action of a fluid, such as steam, compressed air or water, and has for its general object the provision of improved means for facilitating the renewal of any one or more of the conduit sections when said sections become worn through usage.

As is now generally known, ash conveyers of this type are made of several metallic sections forming a conduit, which extends from points at or adjacent furnaces from which ashes are to be removed, to a suitable ash tank or other point where the ashes are to be deposited. In such systems it has been found necessary to make the several elements or sections of the conduit quite heavy and of comparatively large size, on account of the abrasive action of the ashes that are caused to travel therethrough in the normal operation of the conveyer. Because of the considerable weight of the sections and because of the means heretofore employed for supporting the sections of conduit, it has been an extremely difficult matter to effect replacement and repairs when such became necessary.

To overcome this objection to the common type of ash conveyer, I provide certain improved means which permit easy and quick replacement of any of the conduit sections.

A further object of the invention resides in providing a combined support and joint band between two adjacent sections, which, together with the foregoing, will be pointed out in detail in connection with the accompanying drawings, wherein

Figure 1 is a side elevational view of an ash conveyer system embodying the improved arrangements of my invention, some of the parts being shown in section more clearly to reveal the internal construction;

Fig. 2 is an enlarged horizontal cross sec-

tional view taken along the line 2—2 of Fig. 1, looking in the direction indicated by the arrows;

Fig. 3 is an enlarged cross sectional view taken along the line 3—3 of Fig. 1, looking in the direction indicated by the arrows;

Fig. 4 is a side elevational view of an ash conveyer system showing a modified arrangement for supporting the several sections of the ash conveyer conduit;

Fig. 5 is an enlarged horizontal cross sectional view taken along the line 5—5 of Fig. 4, looking in the direction indicated by the arrows; and

Fig. 6 is an enlarged detail cross sectional view taken along the line 6—6 of Fig. 4, looking in the direction indicated by the arrows.

Similar characters of reference refer to similar parts throughout the several views.

Referring first to Fig. 1, the ash conveyer system illustrated comprises a horizontal conduit 7 provided with a plurality of intake hoppers, one of which is shown at 8, the hoppers being disposed at or adjacent the furnaces from which ashes are to be removed. Extending upwardly from one end of the horizontal conduit 7 is the vertical conduit 9 communicating with a second horizontal conduit 10 extending to an ash tank or some other point where the ashes are to be deposited.

Each one of the conduits 7, 9 and 10 is made up of several elements or sections held in place by clamping bands and arranged to be removed from the system when renewal of the sections becomes necessary or desirable. The horizontal conduit 7 is made up of the several semi-cylindrical sections as shown at 11, 12 and 13. The several semi-cylindrical sections, as most clearly illustrated in Fig. 3, coöperate to form a continuous cylindrical pipe unit.

To seal the space provided between the lateral abutting edges of the upper and lower pipe sections, as between the pipe sections 11 and 12, I provide the labyrinth joint shown at 14 in Fig. 3, formed by a longitudinal ridge carried by one of the sections, and a coöperating longitudinal groove formed in the adjacent section, the space between the ridge and walls of the groove being filled with a suitable

filler or grout. The abutting ends of the several sections of the conduit are provided with annular flanges shown at 15 and 16, shaped so as to provide an annular groove 17 between the conduit sections. This groove is filled with grout made up of a fibrous and cementitious fireproof composition, which may be of the kind described and claimed in patent to James A. Daviess, No. 1,278,869, the filler or grout being held in place by the retaining band shown at 18. Each one of the bands 18 is made up of two semi-cylindrical clamping members, each of which carries the two inwardly extending flanges 19 and 20 which embrace the outer faces of the flanges 15 and 16 formed on the pipe sections. The semi-cylindrical bands 18 are bolted or otherwise secured to the T beams 21, 21, one disposed on each side of the horizontal conduit 7 and running parallel with the conduit, as shown in Figs. 1 and 3. The T beams 21 are supported from the floor by the standards shown at 22, 22.

From the construction thus far described it will be observed that all of the sections constituting the horizontal conduit 7 are supported by the T beams 21 through the action of the semi-cylindrical clamps 18. If the removal of the section shown at 11 becomes necessary or desirable, the upper clamps 18 which embrace the ends of the section 11 are removed, with the result that the section 11 is detached from its support. The section may then be removed and repaired or replaced, and the clamps 18 again bolted to the T beams 21.

The elbow forming communication between the horizontal conduit 7 and the vertical conduit 9 is preferably constructed of five parts shown at 23 to 27 inclusive. The section 26 carries two lugs, one of which is shown at 28, for bolting the section to the T beams. 29 designates a steam nozzle extending upwardly into the conduit for the purpose of forcing steam and ashes through the conduit system.

The vertical conduit 9 is preferably made up of several semi-cylindrical pipe sections provided with end flanges 15 and 16 identical with those described in connection with the horizontal conduit 7. The several sections in this vertical conduit are held together by the semi-cylindrical clamping bands 18, which, instead of being clamped to a T beam, as are the clamps associated with the horizontal conduit, are clamped to one another, as most clearly shown at 30 in Figs. 1 and 2. The elbow 31 establishing communication between the vertical conduit 9 and the horizontal conduit 10 may be made up of several parts, as is the lower elbow, or may be made up of one piece, if such is desired. The upper elbow 31 is carried by a support 32 attached to the elbow by

the lugs and bolts shown at 33. If it becomes necessary to remove any one of the sections forming the vertical conduit 9, as for example, if it is found necessary or desirable to remove the section shown at *a*, the clamps *b* and *c* are removed and the section *a* moved transversely out of the conduit 9. It will be observed that all of the sections above the section *a* are suspended from the support 32, and all of the sections beneath the section *a* are supported by the T beams 21, 21. After the new section is put in place the annular grooves between the end flanges 15 and 16 are grouted and the clamps *b* and *c* put back in place.

In the modified arrangement of vertical conduit shown in Fig. 4, I employ two T beams 34, 34, extending upwardly on opposite sides of the conduit, and bolted to each one of the clamps 18—18, as shown in Fig. 5. By this arrangement each one of the conduit sections is supported from the clamp which embraces the upper flange of that particular section. In this arrangement each one of the sections is independently supported from the T beams 34, 34.

From the above description it will be observed that each one of the clamps 18 performs the double function of supporting one or more sections of the conduit, and of retaining the grout in place in the annular groove 17, so that the pressure created within the conduit does not dislodge any of the filler.

Having thus described my invention, what I claim as new and desire to secure by Letters Patent of the United States is:

1. An ash conveyer comprising a conduit consisting of a plurality of sections disposed end to end, a supporting framework for the conduit, and means attached to the framework for sealing the joints between the opposing edges of adjacent sections and for supporting the sections from the framework.

2. An ash conveyer comprising a conduit consisting of a plurality of sections disposed end to end, a supporting framework for the conduit, and clamping bands attached to the framework for supporting said sections and for sealing the opposing edges of adjacent sections.

3. An ash conveyer comprising a conduit consisting of a plurality of semi-cylindrical sections disposed end to end, a supporting framework for the conduit, and clamping bands attached to the framework for supporting said sections and for sealing the opposing edges of adjacent sections.

4. An ash conveyer comprising a conduit consisting of a plurality of sections assembled to provide a continuous passageway, a framework co-extensive with the conduit, and clamping bands for securing each of said sections to the framework.

5. An ash conveyer comprising a plurality of semi-cylindrical pipe sections assembled to provide a continuous conduit, flanges at the ends of each of said sections, grout between adjacent sections, a plurality of bands extending around the flanges for holding the grout in place between the sections, and a framework supporting the said sections through the said bands. 30
- 19 6. A vertically extending conduit for ash conveyers, comprising a pair of sections disposed end to end, a framework for supporting the upper one of said sections, and means for suspending the lower section from the 35 upper section.
- 20 7. A vertically extending conduit for ash conveyers, comprising a pair of semi-cylindrical sections disposed end to end, a framework for supporting the upper one of said sections, and a clamping band for suspending the lower section from the upper section. 40
- 25 8. A vertically disposed conduit for ash conveyers, comprising a plurality of sections placed end to end to form a continuous passageway, a flange at the upper end of each of said sections, and a band extending under each of said flanges for supporting each of 45

said sections independently of sections therebelow.

9. A vertically disposed conduit for ash conveyers, comprising a plurality of sections placed end to end to form a continuous passageway, a flange at the upper end of each of said sections, and a band extending under each of said flanges for supporting each of 35

said sections independently of sections therebelow and for sealing the joints between adjacent sections.

10. A vertical conduit for ash conveyers 40 comprising several sections disposed end to end to provide a continuous passageway, a support for the lower end of the conduit, means for supporting the upper section of the conduit, and means connecting the several sections, whereby the removal of one of said sections causes suspension, of the sections above that removed, from the said upper section.

In witness whereof, I hereunto subscribe 50 my name this 30th day of July, 1919.

LORNE A. GRIFFIN.
